M. JOFFE.
MANURE POUCH.
APPLICATION FILED SEPT. 8, 1915.

Patented Apr. 25, 1916.

UNITED STATES PATENT OFFICE.

MORRIS JOFFE, OF NEW YORK, N. Y.

MANURE-POUCH.

1,181,014.

Specification of Letters Patent. Patented Apr. 25, 1916.

Application filed September 8, 1915. Serial No. 49,562.

To all whom it may concern:

Be it known that I, MORRIS JOFFE, a subject of the Czar of Russia, residing at New York, in the county of New York and State 5 of New York, have invented new and useful Improvements in Manure-Pouches, of which the following is a specification.

This invention relates to manure pouches and has for its primary object the provision 10 of a device of this character designed for attachment to a horse and to be worn while the horse is working and arranged thereon so that the evacuations can be caught and retained in a condition where the same will be 15 held against any unsightly and unsanitary deposit upon the roadway and at the same time accumulated as refuse which from time to time may be conveniently conveyed to some suitable depository.

Another object of the invention resides in 20 the provision of a device of this character which will be so constructed that the waste contents thereof can be readily removed without requiring the removal of the same 25 from the animal.

A still further object of the invention is 30 to provide a device of this character which will be simple in construction, light but strong and durable and of a design whereby it may be readily applied to any ordinary 35 vehicle construction and to the usual harness.

A further object of the invention is to 35 provide a device which may be constructed of a suitable textile material so that it may be readily and thoroughly cleaned and maintained in a sanitary condition.

In the drawings forming a part of this 40 specification and in which like reference numerals indicate similar parts throughout the several views.—Figure 1 is a side view of the device showing the general application thereof. Fig. 2 is a perspective view of the outer container. Fig. 3 is a perspective 45 view of the inner removable container.

In the drawings, it will be seen that the device consists of an outer container 1 which is preferably formed of textile material such as canvas or the like and formed into a substantially 50 apron like wall 2, having guard forming sides 3—3 and from the just mentioned portions the walls of the structure are continued into the walls of a main refuse containing division having a relatively 55 large intake throat 4 and a restricted lower discharge portion 5, whose open end 6 is

adapted to be securely closed by a flap 7. This flap is formed by extending a part of the material of the structure beyond the portion 5 as shown in Fig. 2 of the drawings. 60 Along the edge 8 of the apron 2 are attaching straps 9 which are adapted to be buckled around the breeching strap of the harness, while at the immediate throat end of the structure the wall 5^a is folded over and 65 around a reinforcing and stiffening rod 10, which is provided for the purpose of giving a correct open condition of the intake throat 4. Passing around this strip 10 and through the said wall 5^a are attaching straps 11 70 which are secured to the whiffletree of the wagon. The discharge portion of the container carries a strap 12 having one end of a coil spring 13 secured thereto, the opposite end of said spring being provided with a 75 strap 14 which may be secured about the axle of the wagon. In this manner the end of the structure which, in time will be subjected to weight and strains will be 80 yieldingly supported and the device will be secured against undue injury. By attaching the open throat end to the whiffletree as mentioned, the throat is held in a full opened condition at all times, while it further assists in the action of the spring 13 in 85 accommodating the device to different movements of the animal.

As a means for holding the flap 7 closed, a strap 15 is secured thereto and it carries an eye member 16 which may be connected in 90 a hook 17 which extends from the strip 10 as shown in Fig. 1. The operator may effect a removal of the contents of the device by simply adjusting the flap 7 to the opened position shown in Fig. 2. 95

It may happen that a supplemental container is desired and designed to be temporarily placed within the main outer container 1 and use, therefore can be made of the container 18 which is shown in Fig. 3. 100 This container is substantially of the same form as the outer container, the principal difference residing in the provision along the edge 19 thereof of a plurality of hooks 20 which may be extended over the edge 8 105 of the outer container, while, along the edge 21 of the throat of said inner container are hooks 22 which may be extended over the strap 10 of the outer container. The flap 23 at the discharge end of the container carries a strap 24 having a hook 25 which is 110 adapted to be extended over the edge 21

when the strap 24 is adjusted to one position.

I claim—

1. A manure pouch of the class described, comprising a container having an adjustable closure at one end and an intake throat at its opposite end, means for attaching the throat end to the breeching strap, and means for attaching the closure end to the axle of 10 the vehicle.

2. A manure pouch of the class described, comprising, a container having an adjustable closure at one end and an intake throat at its opposite end, means for yieldingly attaching the throat end to the breeching strap, and means for attaching the closure end to the axle of 15 the vehicle.

3. A manure pouch of the class described, comprising a container having an adjustable closure at one end and an intake throat at its opposite end, means for attaching the throat end to the breeching strap, and means for attaching the closure end to the axle of 20 the vehicle.

the vehicle, a supplemental container removably mounted in the first container, and means for holding the same in an applied position therein.

4. A manure pouch of the class described, comprising a container having an adjustable closure at one end and an intake throat at 30 its opposite end, means for attaching the throat end to the breeching strap, and means for attaching the closure end to the axle of the vehicle, a supplemental container removably mounted in the first container, and means for holding the same in an applied position therein, and comprising devices on the throat of the supplemental container having detachable connection with the throat of the main container.

In testimony whereof I affix my signature in presence of two witnesses.

MORRIS JOFFE.
